UNITED STATES PATENT OFFICE.

FREDERICK H. STUBBE, OF NEW YORK, N. Y., ASSIGNOR OF ONE-HALF TO JOHN C. KLATZL, OF NEW YORK, N. Y.

GASOLENE-FILTER.

1,035,653.

Specification of Letters Patent. Patented Aug. 13, 1912.

Application filed March 6, 1912. Serial No. 681,901.

To all whom it may concern:

Be it known that I, FREDERICK H. STUBBE, a citizen of the United States, and a resident of the city of New York, borough of the Bronx, in the county and State of New York, have invented a new and Improved Gasolene-Filter, of which the following is a full, clear, and exact description.

My invention relates to a new and improved form of gasoline filter, and an object of my invention is to provide a device of the above indicated character from which the water or other heavy substance will be baffled and precipitated from the gasoline before the latter passes through the screens common to devices of this character.

A further object of my invention is to provide a device from which the screens may be readily removed and inserted.

20 A still further object of my invention is to provide a device of the above indicated character which may be readily cleaned and in which the several parts may be quickly assembled or removed.

25 I attain the above outlined objects by constructing a two-part cylinder having an inlet at one end and an outlet at the opposite end. Depending from the side having the inlet is a trap, disposed between which trap 30 and the outlet is a baffle screen having an opening at its upper end, through which opening the gasoline is allowed to pass on its way to suitably disposed screens, which screens are carried in a shell removably 35 placed in the part of the cylinder between the baffle plate and the outlet.

Reference is to be had to the accompanying drawings, forming a part of this specification, in which similar characters of reference indicate corresponding parts in all the figures; and in which—

40 Figure 1 is a vertical sectional view taken through a preferred embodiment of my device; Fig. 2 is a vertical transverse sectional view taken on the line 2—2 of Fig. 1, and looking in the direction of the arrow, and Fig. 3 is an elevation of the baffle plate.

45 Described more in detail, I have shown a cylinder 4, preferably constructed of two substantially equal parts, fastened together by means of a plurality of screws 5 passing through abutting flanges 6 extending from the meeting edge of each half of the cylinder. One portion of the cylinder, herein- 50 after referred to as the "inlet part 7", has

a suitably constructed inlet connection leading thereto. Threaded into a flanged opening 9 in the lower portion of the inlet part 7, is an externally screw-threaded sleeve 10, the lower end of which is engaged by a trap 11 in the form of an inverted dome, the lower end of which has an outlet 12 normally closed by a screw 13. The inlet part 7 has a grooved recess 14 in its flanged end, the shoulder 15 formed by said recess having a plurality of spaced-apart indentations 16 therein. Resting on said shoulder 15 is a substantially segment-shaped baffle plate 17, having teeth 18 projecting therefrom and adapted to engage in the indentations 16, to prevent said plate from rotating in its own plane. The upper straight edge 19 of the plate 17 terminates below the upper side of the bore of the cylinder 4, so as to form an overflow opening 20 for the passage of 75 the gasoline over the baffle. It will be understood that the gasoline coming through the inlet 8 is checked by the baffle plate, permitting water or other heavy liquid or substance to flow through the pipe 10 into the 80 trap 11, and permitting the lighter gasoline to flow over the plate 17.

Disposed in rear of the plate 17 and in the recess 14, is the first screen 21, which screen and plate are held in position by the adjacent edge of the outlet part 22 of the cylinder 4. Bearing upon the screen 21 and extending into the outlet part 22, is a helical spring 29 having an external diameter substantially equal to the diameter of the bore 90 of the cylinder 4, said spring having the convolution 23 at the end opposite the screen 21 of smaller diameter and adapted to fit within a shell 24 and to bear upon a ring 25 slidably mounted in said shell. The shell 95 has positioned therein a plurality of removable screens 26, which screens are held in position between the ring 25 and the peripheral flange 27 forming the outer end of the shell 24. Leading from the outlet part 22 100 of the cylinder 4 is an outlet 28 of any suitable construction.

It will be seen from the above outlined construction that the two portions of the cylinder 4 may be readily disconnected by 105 unfastening the screws 5, thereby permitting the ejection of the spring 29 and the removal of the screen 21 and baffle plate 17. At the same time, the shell 24 and its containing spring may be withdrawn from the 110

open end of the outlet portion 22 and the screens cleaned or new screens inserted in place of old ones.

Having thus described my invention, I claim as new and desire to secure by Letters Patent:

1. A gasolene filter comprising a cylinder having an inlet at one end and an outlet at the opposite end thereof, said cylinder formed of two component parts, abutting flanges carried by said parts, one of said flanges having a recess in the abutting face thereof, a fluid-checking element disposed on the shoulder formed by said recess, said element being held in place by the end of the adjacent part, a screen disposed in said adjacent part, a coil spring having one end supported by said element and the opposite end acting on said screen, and a trap in fluid connection with said cylinder on the side of said element opposite said screen.
2. A gasolene filter comprising a cylinder having an inlet at one end and an outlet at the opposite end thereof, said cylinder formed of two component parts, abutting flanges carried by said parts, one of said flanges having a recess therein, a fluid-checking element disposed within said recess, said element held in place by the end of the adjacent part, a screen disposed in said adjacent part, and a coil spring having one end acting on said element and the opposite end on said screen, to maintain the screen spaced from said element.
3. A gasolene filter comprising a cylinder having an inlet at one end and an outlet at

the opposite end thereof, said cylinder formed of two component parts, abutting flanges carried by said parts, one of said flanges having a recess therein, and a fluid-checking element disposed in said recess, said member being held in place by the end of the adjacent part.

4. A gasolene filter comprising a cylinder having an inlet at one end and an outlet at the opposite end thereof, a shell disposed within said cylinder, a screen carried by said shell, a ring within said shell and bearing on said screen to hold the same in position, and a spring bearing on said ring to maintain said ring in contact with said screen.

5. The herein described gasolene filter comprising, in combination, a cylinder having inlet and outlet openings, a vertical solid baffle plate fixed in said cylinder between said openings, said plate being adapted to check the flow of gasolene but permitting the same to flow thereover after being checked, a plurality of screens between the plate and the outlet opening, and a spring acting to maintain said screens in spaced relation, the force of the spring at one end being resisted by said plate.

In testimony whereof I have signed my name to this specification in the presence of two subscribing witnesses.

FREDERICK H. STUBBE.
